[57] CLAIM

The ornamental design for a collapsible trash receptacle, as shown and described.

DESCRIPTION

FIG. 1 is a top and side perspective view of a collapsible trash receptacle, in an open condition, showing my new design;

FIG. 2 is a side elevational view thereof in a closed, partially collapsed condition, the opposite side view being a mirror image of that shown;

FIG. 3 is a side elevational view thereof in an open, partially collapsed condition;

FIG. 4 is a rear elevational view thereof in an open condition; and

FIG. 5 is a top plan view of FIG. 1.

FIG. 1

FIG. 2

FIG. 3

FIG. 4

FIG. 5
